UNITED STATES PATENT OFFICE.

EDWARD HAMMANN, OF BROOKLYN, NEW YORK, ASSIGNOR TO THE J. L. MOTT IRON WORKS, OF NEW YORK, N. Y.

DESIGN FOR A CISTERNS FOR WATER-CLOSETS.

SPECIFICATION forming part of Design No. 26,841, dated March 30, 1897.

Application filed February 15, 1897. Serial No. 623,577. Term of patent 7 years.

To all whom it may concern:

Be it known that I, EDWARD HAMMANN, a citizen of the United States, residing at Brooklyn, in the county of Kings and State 5 of New York, have invented and produced a new and original Design for a Cistern for Water-Closets, of which the following is a specification.

The leading feature of this design for a cistern for water-closets consists in the inverted conical configuration shown in the drawings, wherein—

Figure 1 is a vertical section. Fig. 2 is a plan view, and Fig. 3 is a side elevation.

The lower end *a* is smallest, the back *b* is 15 vertical, the sides *c* are inclined, and the front is slightly inclined, so that the top *d* is oblong.

I claim—

The design for a cistern for water-closets, 20 substantially as described and shown.

Signed by me this 11th day of February, 1897.

EDWARD HAMMANN.
